UNITED STATES PATENT OFFICE.

WALTER H. SERGENT, OF MIDDLETOWN, NEW YORK, ASSIGNOR TO IDEAL WRAPPING MACHINE COMPANY, A CORPORATION OF NEW YORK.

ARTICLE RECEIVER.

Original application filed January 9, 1922, Serial No. 527,828. Divided and this application filed December 28, 1923. Serial No. 683,138.

This invention relates to a discharge box for a caramel wrapping machine or the like, into which the wrapped caramels are discharged from a wrapping wheel. This application is a division of my co-pending application for caramel wrapping machine Serial No. 527,828, filed January 9, 1922.

It is an object of this invention to provide a discharge box of the character stated for folding and pressing the wrapper upon an article such as a cube of candy and holding the same while the final folds are made, and which is yieldingly supported for lateral movement.

The invention comprises the novel mechanism and combinations hereinafter described and more particularly pointed out and defined in the appended claims.

In the accompanying drawings which illustrate a preferred embodiment of this invention and in which similar reference numerals refer to similar features in the different views.

Figure 1 is a horizontal sectional view through the caramel discharge box.

Figure 2 is a vertical section through the box.

Figure 3 is an elevational view of the discharge box and adjacent mechanism of the machine.

Referring to the drawing, 1 represents a horizontal support extending outwardly from the rear wall of the caramel wrapping machine adjacent the rotary wrapping wheel 2. A bracket 3 is clamped upon the end of the support 1. The upper end of the bracket 3 is flat, and adjacent the upper end, it supports an outwardly extending rod 4. The caramel discharge box 5 has its inner portion resting upon the bracket 3 and it is provided with a depending shoulder 6 suitably apertured for receiving the rod 4. The depending shoulder 6 abuts the side of the bracket 3 and a yielding abutment in the form of a coiled spring 7 positioned upon the rod 4 and confined between the shoulder 6 and a nut 8 on the end of the rod, yieldingly urges the shoulder 6 of the discharge box against the bracket 3. The discharge box has a polygonal opening or passage 9 extending therethrough through which the wrapped cubes of candy are adapted to pass. The sides and the top of the passage 9 are lined with resilient plates

10 which are pivoted or hinged to blocks 11 secured to the outer ends of the sides and top of the box. Sockets 12 are formed in the top and sides of the discharge box at suitable points forward of the pivotal points of the plates 10. Coil springs 13 are confined in said sockets for yieldingly bearing upon the plates 10 and urging the same together. Adjustable plugs 14 may close the outer ends of the sockets if desired, an adjustment of which will vary the tension of the coil springs 13. The bottom of the discharge box is lined by a smooth plate 15.

The rear end of the bottom of the discharge box projects rearwardly to form a ledge 16 which is recessed in registry with the passage through the discharge box. A discharge chute 17 having a bottom lug 18 fitting in said recess is pivoted by means of a removable rod 19 to said ledge 16.

The caramel cubes are adapted to be ejected from the wrapping wheel 2 into the discharge box 5 and retained by the resilient plates 10 while the final folders 20 swipe the ends of the projecting wrapper for folding the same. For thuswise holding the cubes of caramel, the inner ends of the plates 10 are deflected toward the center of the discharge passage as indicated at 10^a.

If the caramel cube should for any reason become jammed between the discharge box and the wrapping wheel, the former may yield against the tension of the spring 7. And if better access should at any time be desired between the wrapping wheel and discharge box, the latter may be shifted outwardly against the tension of the spring 7 by grasping the handle 21 depending from the shoulder 6 thereof.

I am aware that many changes may be made, and numerous details of construction may be varied through a wide range without departing from the principles of this invention, and I therefore do not purpose limiting the patent granted hereon, otherwise than necessitated by the prior art.

I claim as my invention:

1. In a candy wrapping machine, a discharge box, a support therefor having an outwardly extending element, yielding means supported upon said element for yieldingly maintaining said box in position.

2. In a caramel wrapping machine, a discharge box, a support therefor comprising

a yielding abutment for allowing lateral movement of the box.

3. In a caramel wrapping machine, a discharge box open at each end, plates hinged-
5 ly connected to the inner wall thereof and yielding means in the wall of said box act-
ing upon said plates.

4. In a caramel wrapping machine, a dis-

charge box open at each end, plates hinged-
10 ly connected to the inner wall thereof and yielding means between said plates and wall.

In testimony whereof I have hereunto subscribed my name.

WALTER H. SERGENT.
